UNITED STATES PATENT OFFICE.

JOSEPH HUNTER ROSS, OF WASHINGTON, DISTRICT OF COLUMBIA.

DEMURRAGE CHART SYSTEM.

Application filed December 31, 1921. Serial No. 526,350.

To all whom it may concern:

Be it known that I, JOSEPH HUNTER Ross, a citizen of the United States, residing at Washington, in the District of Columbia, have invented certain new and useful Improvements in Demurrage Chart Systems, of which the following is a specification.

This invention relates to a novel chart system for checking and recording demurrage charges accruing on railroad rolling stock.

To that end the invention contemplates a series of charts having diagrams adapted to be provided with designations for accurately indicating the number, movement and status of cars in private yards or on unloading sidings. It is wellknown that mills, elevators, warehouses and like consignees or shippers usually have a so-called yard consisting of suitable trackage especially designated to receive cars delivered or consigned thereto by the railroad for loading or unloading purposes. Usually such a yard includes an unloading track or tracks having a definite car capacity and frequently the number of cars delivered to the consignee are in excess of the capacity of the unloading tracks and therefore it becomes necessary to hold over such excess cars until they can be loaded or unloaded, as the case may be, and removed by the railroad. If the car is held over a certain time limit set by the carrier, a fine or fee is assessed for the additional time that the car is held over and this fine is commonly called demurrage.

While it is quite well understood that the demurrage charges are incommensurate with the investment in the equipment, nevertheless, such a charge constitutes the penalty for failure to expedite the prompt loading or unloading of equipment after the same has been properly placed upon the delivery tracks. Due to numerous considerations entering into the calculation of demurrage charges, such for example as constructive delivery, that is, when the consignee is notified by the carrier that they are ready to deliver the car to him regardless of his facilities for handling the same; the unloading of some cars in less than the free time leaving a balance of free time to be applied to the handling of other cars; the denial of the actual receipt of a car by the consignee or shipper; loss of checking slips and the like, it is very difficult under the present system to keep accurate account of

car movements. Obviously, therefore, in the absence of some reliable and easily visualized record for checking the handling and movement of the cars, the amount of the demurrage charge is open to dispute.

Heretofore, the carriers or railroads have maintained loose checking slips, such as switching lists or daily car track records in the usual column or tabulated form, which, while containing a certain amount of data relating to each car, do not in themselves serve to bring out clearly the definite movement of a car after it reaches its point of destination. From lists of this type it is possible to visualize the movement of the cars in such a positive and definite manner that anyone not skilled in the technique of car checking can readily understand how the demurrage accrued and whether or not the amount thereof is correct.

Accordingly, the present invention has primarily in view a novel chart system which visualizes very clearly in diagrammatic form the actual delivery and movement of each and every car to any given yard and unloading track. That is to say, the invention contemplates a novel yard chart having diagrams provided with designations indicating the total number of loaded cars available in the yard and the total number of unloading positions, together with a novel measuring symbol indicating the proportional number of cars which can occupy the unloading tracks between shifts thereby making it possible to definitely ascertain how long a car must be held before it can be manipulated into a position to receive or discharge its load. In that way it is possible to definitely ascertain the length of time which any given car is held before it is moved into position on the unloading track. This yard chart cooperates with a primary record chart that receives in addition to the car record an arbitrary index symbol for the car thereby enabling it to be followed up throughout the series of novel track charts on which the status of the car is further designated by other novel symbols indicating that it is loaded, unloaded, held over or empty.

Another object of the invention, in addition to the foregoing general object, is to provide a checking system which provides for keeping track of the date of receipt of such car which will enable anyone inspecting the chart to examine it in connection

with a novel embargo diagram to tell whether or not such a car was received in an embargo period or in a demurrage period without the necessity of consulting numerous records.

10 A further object of the invention is to provide a checking system that may be readily adapted to any industry or yard plan, and which is susceptible of universal application to modern railway rules, stock handling regulations and tariff conditions.

15 With the above and other objects in view which will more readily appear as the nature of the invention is better understood, the same consists in the novel construction, combination and arrangement of parts hereinafter more fully described, illustrated and claimed.

20 A preferred and practical embodiment of the invention is shown in the accompanying drawings in which,

Figure 1 is a diagrammatic view illustrating the yard chart.

25 Figure 2 is a fragmentary view of the consignee's or shipper's primary record chart.

30 Figures 3, 4 and 5 are fragmentary views of portions of unloading track charts, the said views illustrating the loading, unloading, held over or empty status of the cars at the end of three successive shifts.

35 Figure 6 is a detail view of a portion of the embargo chart.

Similar reference characters designate 35 corresponding parts throughout the several figures of the drawings.

40 In its general aspect the present invention involves a series of correlated charts having diagrams for conveniently receiving definite symbols for indicating the status of the cars in order of their receipt by the consignee or shipper and their manipulation upon his tracks by the railroad company. These charts may be conveniently designated as the yard chart A, the primary record chart B for the consignee or shipper, a series of track charts C, C', C'', etc., representing the position of cars at the "check up" at the time of the daily shifts, and the embargo chart D.

45 In connection with the yard chart A, it is proposed to use a definite symbol for indicating the ratio of the capacity of the unloading track to the capacity of the yard. This symbol is preferably in the form of a funnel F which is to be regarded as a measuring symbol for indicating the relatively constricted throat through which the cars awaiting placement must pass to be positioned on the unloading tracks. Or in other words, it symbolizes the entrance or exit to the unloading track and by which its capacity is regulated.

50 For the purpose of readily visualizing and identifying a car as soon as it is delivered

to the consignee or shipper within the territory of his yard, each car is given an index symbol w which may be a numeral or number as for example "60" which may indicate, in the example under consideration, 70 the order of its receipt into the yard and its position on the primary record chart B. This numeral "60" constitutes an index or "follow-up" identification for the particular car to which it is given through the present 75 system and it will represent or indicate the name of the railroad, the number of the car of that road and all other necessary data for such car, as indicated by the headings of the various columns on the primary record 80 chart B.

To indicate the status of the car, that is, loaded, hold over or empty, the symbols x, y, and z are employed. The symbol x is preferably a heavy black line or rectangle 85 and is intended to indicate that a car is loaded when it is placed within the consignee's or shipper's yard and, if for any reason the said car is held over from one shift to the next, it is underscored by the red line y which is the "hold over" symbol. When the car is unloaded its position is designated by an ellipse or hollow oval z which is the "empty" symbol and shows that the consignee or shipper is through with 95 the car. If the car is held over on the unloading track after it is empty it may also be designated as a "hold over" by placing the red line y beneath the ellipse z.

With the foregoing symbols it will be 100 apparent that the car may be readily identified at a glance on any of the various charts and its status, that is loaded, held over or empty, may also be quickly determined.

105 Referring now to the manner in which the charts are related and utilized one in connection with the other it may be observed that the yard chart A illustrates a consignee's or shipper's yard having an unloading track A', capable of accommodating ten cars. To indicate the number of cars that said track may accommodate the same is divided into spaces or stalls A² while the feeder tracks A³ leading from the yard tracks A⁴ 110 to the unloading track converge into the funnel F, indicating that all the cars from the yard must pass over the feeder tracks and through the funnel in order to be placed on or withdrawn from the unloading track A'. 115

120 In the illustration shown in Figure 1 of the drawings, it will be understood that the unloading track A' can only accommodate ten cars while the yard tracks A⁴ on a given date contained thirty cars. As there are 125 usually only two shifts made each day by the railroad company, one in the morning and one in the evening, it would be impossible for all of the thirty cars to pass through the funnel F, even if the unloading track 130

was cleared each shift, in less than three successive shifts. Therefore, if the car is delivered by the carrier on the yard tracks A⁴, and a known number of cars are ahead of 5 such a car, it can be definitely calculated how long it should take a given car to be placed on the unloading siding by the railroad company if it were taken up in its proper order.

10 When a car is "placed," that is, delivered by the carrier to the consignee's or shipper's yard, it should be placed on the yard chart A and its status indicated either as loaded or empty by utilizing the symbol *x* or *z*, while 15 at the same time the data of that car should be placed on the primary record chart B at which time the index symbol is also assigned to that particular car. This index symbol is preferably a number or numeral which is 20 utilized throughout the remainder of the checking system as a substitute or symbol for all of the data concerning the car placed on the primary record chart B.

To illustrate, suppose that car #60 was 25 constructively placed by the railroad company with the consignee on October 20, 1919 at 3 p. m. As shown by the yard chart A in Figure 1 and the primary record chart B. According to the symbol *x* car #60 was 30 loaded when it was constructively placed by the carrier with the consignee on October 20, 1919, and, owing to the number of cars ahead of #60 and the limited capacity of the unloading track A', it was impossible for 35 the railroad company to actually place car #60 on the unloading track A' until October 27 on the 6 p. m. shift, as indicated by the track Chart C, Figure 3.

Therefore, at 6 p. m. on October 27, 1919, 40 car #60 had passed through the funnel F and occupied stall #4 on unloading track A' as designated by the symbol *x* in Figure 3.

On the next shift on the following morning, namely 7 a. m., October 28, 1919, car 45 #60 was held over and still loaded, as indicated by the symbols *x* and *y* in Figure 4. In this figure car #60 occupies stall #7 where it remained until it was unloaded prior to the "check up" and shift made at 6 50 p. m. on October 29, 1919, and illustrated in Figure 5. In Figure 5 it will be observed that car #60 occupied stall #7 on unloading track A', as designated by the ellipse *z*, which indicates that the car is empty and

55 ready for removal from the unloading track by the carrier. In other words it was released on October 29 at 6 p. m., as shown by the track C², and which fact is recorded on the primary record chart B. From the data 60 appearing in connection with car #60 on the primary record chart B, it will be observed that six days demurrage charges are due.

Obviously, any other car may be traced with equal facility during its presence within 65 in the consignee's or shipper's yard and

while on his unloading track by simply applying the arbitrary car designating symbol opposite each space or stall on the unloading track that the car occupies after each shift. Also through the medium of the symbols, 70 *x*, *y* and *z*, it can be readily determined at a glance whether the car was loaded, empty or held over without the necessity of making detailed explanation or reference to that fact on the chart.

75 Another novel and distinctive feature of the invention is the provision of the embargo chart D, shown in Figure 6. This chart consists of a calendar strip D' having the days of each month arranged linearly 80 across the sheet in such a manner that the demurrage and embargo periods may be readily marked or distinguished. That is to say, this chart enables anyone to tell at a glance the period when all cars are exempt 85 from demurrage charges by marking the embargo period with a distinctive color line D², red for example, while the demurrage period may be marked with contrasting color lines D³, blue for example.

90 As the primary record chart B contains the date of the constructive, as well as the actual, placing of the car, with such a date as a guide the merest inspection of the embargo chart in connection with such a date 95 will tell whether or not the car is liable or exempt from demurrage charges. Therefore, the embargo chart D is correlated to the primary record chart B.

An example of the operation of the embargo chart is as follows:—

The embargo chart, as previously indicated, contains the days of the months in linear succession and therefore readily readable at a glance in connection with the 105 name of the month appearing above the same. Since the primary record chart B shown in Figure 2 always contains the date of the constructive as well as the actual placing of the car, with the constructive date as a guide, for example October 10th, the embargo chart may be examined and the date of October 10th will show, due to the lines D³ that such date was in 110 a demurrage period and therefore demurrage was collectable. On the other hand if the date of November 10th should be taken as the key from the primary record chart B, immediately upon reference to the 115 embargo chart, which is lined to indicate an embargo period it will be ascertained at a glance that demurrage was not collectable when the car was placed.

From the foregoing it will be apparent that the novel and distinctive features of 125 the present invention are the provision of a series of novel correlated charts and symbols for designating the ratio of the capacity of the unloading facilities to the number of cars actually or constructively 130

received, and also keeping accurate account of their status while chargeable to a consignee or shipper.

Without further description it is thought that the many features and advantages of the invention will be readily apparent to those skilled in the art, and it will of course be understood that changes in the form, and other minor details of the arrangement may be resorted to without departing from the spirit of the invention or scope of the appended claims.

I claim:

1. A demurrage chart system including a chart having diagrams provided with designations indicating total number of loaded cars available in yard, total number of unloading positions, and symbols which respectively identify each car and its loaded or unloaded status.

2. A demurrage chart system including a chart having diagrams provided with designations indicating total number of loaded cars available in yard, total number of unloading positions, and a measuring symbol visualizing the proportional number of cars which can occupy the unloading station between car shifts.

3. A demurrage chart system for railway cars including a primary record chart having spaces bearing designations containing full data of a given car and an additional special index symbol for demurrage checking, and a series of track charts having spaces bearing designations and symbols respectively showing the special index of a given car and its status as to being loaded, empty or held over.

4. A demurrage chart system for railway cars including a yard chart having a diagram indicating an unloading track and a yard connected therewith by feeder tracks, and a measuring symbol arranged between the feeder tracks and the unloading track for visualizing the proportional number of cars which can occupy the unloading track between shifts.

5. A demurrage chart system for checking the status of railway cars including a yard chart provided with delineated car designation receiving spaces, a primary

record chart provided with data receiving spaces, an arbitrary index symbol adapted to be placed in one of said spaces to identify a designated car on the yard chart, a series of track charts also provided with delineated car designation receiving spaces, and a series of status indicating symbols adapted to be applied to the spaces of said yard and track charts to indicate whether the cars are loaded, held over or empty.

6. A demurrage chart system for checking the status of railway cars including a yard chart provided with delineated car designation receiving spaces, a primary record chart also provided with spaces for receiving an arbitrary index symbol adapted to be placed in one of said spaces to identify a designated car on the yard chart, a series of track charts provided with delineated car designation receiving spaces corresponding to similar spaces on the yard chart, and a series of status indicating symbols adapted to be applied to the spaces of said charts to indicate whether the cars are loaded, held over, or empty.

7. A demurrage chart system for railway cars including a series of co-related charts having diagrams of yard and unloading tracks provided with delineated car designation receiving spaces, a main index symbol for indentifying the car on all of the charts, and a series of status indicating symbols adapted to be applied to the spaces of said charts to indicate whether the cars are loaded, held over or empty.

8. A demurrage chart system for railway cars including a series of charts, certain of said charts having spaces bearing data designating a given car by symbols showing its demurrage status, and also including spaces for dates, and one of said charts being a calendar having the dates of each month arranged in linear succession and provided with designations indicating periods of embargo and demurrage.

In testimony whereof I hereunto affix my signature in the presence of a witness.

JOS. HUNTER ROSS.

Witness:

EMORY L. GROFF.
